(57) **CLAIM**

The ornamental design for a light emitting diode, as shown and described.

DESCRIPTION

FIG. 1 is a perspective view of a light emitting diode showing the claimed design;

FIG. 2 is another perspective view thereof;

FIG. 3 is a front elevational view thereof;

FIG. 4 is a rear side elevational view thereof;

FIG. 5 is a left side elevational view thereof;

FIG. 6 is a right side elevational view thereof;

FIG. 7 is a bottom plan view thereof; the top plan view being a mirror image of the bottom plan view; and,

FIG. 8 is a view showing the visible inner structure through the dome-like light transmissible portion.

The dome-like light-transmissible portion of the design is made of light-transmissible material, which can be frosted, translucent, or transparent. The broken lines are directed to environmental features and are for illustrative purpose only; the broken lines form no part of the claimed design.
